UNITED STATES PATENT OFFICE

128,189

DESIGN FOR A TEXTILE FABRIC OR SIMILAR ARTICLE

Robert Finkelstein, Woonsocket, R. I.

Application March 14, 1941, Serial No. 99,596

Term of patent 3½ years

To all whom it may concern:

Be it known that I, Robert Finkelstein, a citizen of the United States, residing at Woonsocket, in the county of Providence and State of Rhode Island, have invented a new, original, and ornamental Design for a Textile Fabric or Similar Article, of which the following is a specification, reference being had to the accompanying drawing, forming a part thereof.

The figure is a plan view of a portion of textile fabric or similar article, showing my new design, a complete unit of which is contained between the broken lines, the extensions beyond the broken lines indicating a continuation of the design.

I claim:

The ornamental design for a textile fabric or similar article, substantially as shown and described.

ROBERT FINKELSTEIN.
